(57) **CLAIM**

We claim the ornamental design for a trigger guard and magazine latch assembly, as shown and described.

DESCRIPTION

FIG. 1 is a perspective view of a trigger guard and a magazine latch assembly disposed on a firearm according to the disclosure;

FIG. 2 is a bottom perspective view of the trigger guard and the magazine latch assembly according to the disclosure;

FIG. 3 is a top view thereof;

FIG. 4 is a bottom view thereof;

FIG. 5 is a side view thereof;

FIG. 6 is a side view thereof;

FIG. 7 is a front view thereof; and,

FIG. 8 is a rear view thereof.

The evenly broken lines in the drawings depict unclaimed subject matter, and the dash-dot broken lines illustrate the bounds of the claimed subject matter. The evenly broken lines and the dash-dot broken lines do not form a part of the claimed design.
